UNITED STATES PATENT OFFICE.

WILLIAM W. LASKER, OF BROOKLYN, NEW YORK, ASSIGNOR, BY MESNE ASSIGNMENTS, TO POWERS ACCOUNTING MACHINE CORPORATION, OF NEW YORK, N. Y., A CORPORATION OF DELAWARE.

SORTING MACHINE.

Application filed March, 17, 1923. Serial No. 544,417.

To all whom it may concern:

Be it known that I, WILLIAM W. LASKER, a citizen of the United States, residing in Brooklyn, in the county of Kings and State of New York, have invented certain new and useful Improvements in Sorting Machines, of which the following is a specification:

My invention relates broadly and generally to new and useful improvements in machines for sorting or classifying perforated cards, such, for example, as are used in automatic calculating and adding machines, and more particularly to machines of the general character or type disclosed in Letters Patent No. 1,315,370, dated September 9, 1919.

The object of the invention is to provide a sorting machine which will be highly efficient, of a great degree of accuracy and certainty in operation, and which at the same time will operate at an increased speed in sorting the cards, without detracting from the desirable accuracy and efficiency.

The invention consists in the improvements and novel construction of elements and their aggroupment in operative combination, to be more fully described hereinafter, and the novelty of which will be particularly pointed out and distinctly claimed.

I have fully and clearly illustrated a preferred embodiment of my invention in the accompanying drawings to be taken as a part of these specifications, and wherein—

Figure 1 is a top plan view, partly in section, and with certain parts removed and broken away for the sake of clearness, showing a preferred embodiment of my invention;

Fig. 2 is a longitudinal section on the line 2—2 of Fig. 1;

Fig. 3 is a transverse section on the line 3—3 of Fig. 1;

Fig. 4 is a detail sectional view on the line 4—4 of Fig. 3;

Fig. 5 is an enlarged detail sectional view of certain elements shown in Fig. 3;

Fig. 6 is a detail view, partly in section, of certain mechanism shown in plan at the lower left-hand corner of Fig. 1;

Fig. 7 is a detail view of a settable timing mechanism for operating certain means for controlling entrance or receipt of a card at its designated station;

Fig. 8 is a detail sectional view on the line 8—8 of Fig. 7; and

Fig. 9 is a plan view of one type of card which the machine of my invention is adapted to sort or classify.

Referring to the drawings by characters of reference, and particularly to Figs. 1, 2 and 3; 1, 1 designates side members of a supporting frame for certain mechanisms of the machine, said members being preferably in the form of vertical parallel plates, the bases of which are adapted to be supported in any suitable manner upon a foundation or stand (not shown). These plates 1, 1 serve to support feeding mechanism, analyzing mechanism, and associated parts, as will be more fully described hereinafter, said plates being maintained in vertical parallelism by means of horizontal tie rods 2 of any suitable construction and arrangement.

The card feeding means may be of any suitable construction for successively advancing or projecting cards one at a time from a stack or other supply, for example, said means may, if desired, be the same as that shown and described in the Letters Patent above mentioned. Briefly described, said means comprises a magazine or hopper 3 rigidly mounted on the said members 1, and adapted to support a pack or stack of horizontally disposed cards to be sorted. This magazine is open at its bottom portion, and beneath the same is arranged a reciprocating feed block 4, guided in guides 4^a at the lower part of the magazine, and having on its under side a lug 5 connected by means of a link 6 to the upper end of a lever 7 rigidly mounted on a horizontal rock-shaft 8 mounted in suitable bearings 9 in the frame members 1. The lever 7 is connected, as at 10, to one end of a lever or eccentric rod, provided with an eccentric strap 11, mounted on an eccentric 12 fixed on a horizontal shaft 13, mounted in suitable bearings 13^a in the side frames 1, and driven by suitable means, as will be hereinafter described, whereby the block 4 is reciprocated across the lower part of the magazine. The block 4 is provided at its rear portion with a transverse rocker blade 14 projecting a proper distance above the upper face of the block 4, so as to extend behind and be in a position to engage

13^a 13 12 11 10 9 8 7 6 5 4 4^a 3 3^a 2 1 1^a

the rear edge of the lowermost card in the stack contained in the magazine 3. The forward portion of the magazine is provided with a micrometer slot 15, so that when the block 4 is moved forward a card engaged by said blade 14 will be projected through said slot 15 to be presented to analyzing means to be presently described. I wish it understood that my present invention is not limited to 10 any particular means for feeding the cards to the analyzing mechanism, the means thus briefly described being but one which may be efficiently employed.

When the card is projected through the 15 slot 14, it is received by a suitable transferring means, which may consist of an upper roller 16 mounted on a horizontal shaft 17, and a cooperating lower roller 18 mounted on a horizontal shaft 19, said rollers frictionally 20 engaging each other, and the lower shaft carrying a grooved belt-pulley 20 driven by a power belt 21 driven by any suitable source of power, preferably an electric motor (not shown). On the shaft 17 (see Fig. 6) is 25 fixed a pinion 22 which meshes with a pinion 23 fixed on the shaft 19, the pinion 23 meshing with a pinion 24 on the stud shaft 25, the latter carrying a second pinion 26 which in turn meshes with a large gear 27 fixed to 30 the shaft 13, heretofore described, whereby the latter is rotated to actuate the connecting rod to reciprocate the feed block 4, heretofore described. The drive just described also serves to rotate the rolls 16, 18 to 35 present the cards successively to analyzing means for detecting the characteristics or designations which determine the sorting or classification of cards. In part, this analyzing means (see Fig. 4) comprises upper and 40 lower plates 28, 29, which are suitably supported on the frame, and which are suitably spaced to receive between them a card A to be analyzed. These plates will be more fully described hereinafter. Beneath the plate 29 are arranged horizontal shafts 30, 31 mounted in bearings 30^a (see Fig. 3), each shaft carrying feed rollers 32, the peripheries of which project through openings in the plate 29 and engage the under face of a card outside the perforated area thereof to feed the card from between the plates at the proper time. When the card has been analyzed, and is fed forward by the rollers 32, it is caught 55 between upper and lower contacting transmission rolls 33, mounted on shafts 34, 35, respectively, and is moved forward toward the receiving station or depository which has been previously determined by the analyzing means to receive the card. The shaft 30 is 60 driven by the gear 24, which meshes with a gear 36 mounted on said shaft (Fig. 6). The gear 27 meshes with a small gear 37 on a skid shaft 38, which also carries a gear 39 meshing with a gear 40 on shaft 31, whereby the latter, and the rollers

carried thereby, are driven. The gear 39 also meshes with a gear 41 on the shaft 35, and the gear 41 meshes with a gear 42 on the shaft 34, whereby the rolls 33 are driven to feed the card forward as described. Over 70 the upper pin plate 28, are rollers 28^a (see Figs. 1 and 5) projecting through openings 28^b in said plate, and cooperating with the driven rollers 32. The rollers 28^a are each mounted on one arm of a bell-crank lever 28^c 75 fulcrumed, as at 28^c, on a bracket 28^a, on a plate 28^d held by screws 28^e on the upper side of the plate 28. The other arm 28^b of each bell-crank lever projects upward, and the said arms of the bell-cranks at each end of the plate 28 are connected by a tension spring 28^f, whereby the rolls 28^a are swung downward towards the rollers 32.

I will now describe one type of card, by way of example, adapted to be sorted by my present invention, and will then proceed to describe analyzing means for determining the character or classification of the card or cards to be classified or sorted, and which serves to control the receipt or deposit of the 90 card or cards at the proper receiving station or depository.

Upon reference to Fig. 9 of the drawings, it will be seen that the card A therein shown is divided into a plurality of parallel columns *a*, each of which is allotted to certain data or designations which it is desired to have recorded by the card. Each of these columns comprises a plurality of spaces *b*, certain of which are adapted to be punched in order to record desired data or designations upon the card; for example, the column *c* may be employed to record data as to months during which certain transactions, entries or events take place, and the space allotted to the month of the transaction, for example, the space allotted to February is perforated if that is the item desired to be recorded. It will be noted that the spaces in each column are in vertical alignment, viewing the card from its front longitudinal edge, and also that corresponding spaces in all of the columns register lengthwise of the card, that is, the first space in each column aligns with the first space in the other columns, and so on. If the cards are to be classified according to months, by way of example, the machine may be set so as to sort out all cards of the same month and deposit them at a suitable station, so that all cards for that month will be selected from a number of cards having perforations in the column *c* in spaces allotted to different months, that is, the machine may be set to pick out and classify all card for the month of February, or for two or more months, depositing those for each month together at a proper individual station. The improved means for accomplishing this result will now be described:

The analyzing means (see particularly Figs. 4 and 5) comprises the plates 28, 29, heretofore mentioned, which plates are adapted to receive and support between them a perforated card, for example, like that shown in Fig. 9, said plates being perforated, respectively, with openings 43, 44, arranged in rows in longitudinal and transverse alining rows, as shown in Fig. 1, corresponding to the arrangement of the areas on the cooperating card, which are adapted to be punched, and control the operation of the machine. The arrangement is such that when a card to be sorted passes to the analyzer and between the plates 28, 29, the areas on the card will register with alining corresponding perforations in said plates, and any perforated areas in the card will register with the plate openings, for a purpose to be presently described.

Arranged over the plates 28, 29 are transverse horizontal bars 45, upon which are slidably mounted brackets or ears 46 carried on the front and rear walls 47 of a carrier, preferably in the form of a box, and containing analyzer or detector elements adapted to cooperate with the perforations in the plates 28, 29, in order to feel or detect any card perforation which may be in register with any upper and lower alining perforations in said plates. In the present embodiment, the detector elements comprise a plurality of pins 48 arranged in alinement in a row transversely from front to rear of the pin-box, and extending lengthwise of the machine and slidably mounted in openings in a guide bar 49, the ends of which are rigidly secured to the plates 47. Connected to the upper ends of these pins are vertical connector bars 50, the upper end of each of which is pivoted, as at 51, to an intermediate point on a lever 52, one end of which lever is mounted to rock on a horizontal shaft 53 carried by the said plates 47. The lever 52 is provided at its free end with a latch recess 55 adapted to take position under a transverse latch bar 56 mounted on a pivot bar 57 supported in the side plates 47, and to which is rigidly connected end arms 58, the free ends of which are connected by a bar 59, the arrangement being such as to provide a bell-crank motion on the bar 57 as a fulcrum. The levers 52 are arranged to rock in the spaces between the teeth or fingers 52^a of a guide comb 52^a, rigidly supported at its ends in any suitable manner by the plates 47. The bar 56 is normally urged toward the ends of the levers 52 by means of a torsion spring 60 surrounding the bar 57 and having one end suitably secured to said bar 56, and its other end anchored, in any suitable manner, to a collar 61 secured to the bar 57 by a set screw 62. Beneath the levers 52 is a transversely extending stop bar 63 connected to

the end plates 47, and with which is adapted to cooperate stop arms 64 on lower sides of the levers 52, whereby the projecting movement of the pins 48 relative to the carrier or pin-box is limited. Connected to the bar 63 is one end of a spring 65, the other end of which is connected to one arm 66 of a bell-crank lever 67, which is fulcrumed at its angle on the pivot 51 heretofore described. The other arm 68 of the bell-crank lever 67 extends upward and is provided on the side toward the bar 56 with an arm 69 having at its end a locking recess 70. The arrangement is such that when the pin-box is moved toward the card-holding plates, by means to be hereinafter described, certain of the pins will pass through perforations in the plates and registering perforations in the card, and others will be arrested and held by the imperforated portions of the card. One or all of the pins which cannot pass through the card will be held stationary, resting on the imperforate card surface when the pin-box descends, which will result in the lever 52 attached to any such arrested pin being moved to the position shown in shaded lines in Fig. 5, which will throw its lever 68 into engagement with the bar 59, the latter being received by a recess 71. This movement serves to throw the lever 58 toward the left of Fig. 5, thereby causing the bar 56 to be thrown to the right and over the locking recesses 55 on the levers 52 which are connected to pins 48 which are in line with perforations in the card, so that these pins are rigidly connected to the pin-box and move positively therewith in the movement of the latter toward the card. This rigid connection is for a purpose to be presently described. Upon the return or upward movement of the pin-box all of the levers, pins and elements just described return to the normal position shown in Fig. 3 of the drawings. The pin-selecting means, heretofore described, is adapted to sort according to any determined single hole in a column in a card, for example, to cooperate only with those cards which are perforated, say, in the March area of the month column, under which circumstances only those cards having such perforation will be sorted out and collected in the appropriate depository, this being an example of what is known in the art as "split sorting." In this case but one of the pins 48 will be employed, and the remainder rendered inactive, this being accomplished by grasping the lever 68 of each pin desired to be inactive and engaging its locking recess 70 with the bar 59, whereby any pin or pins attached to such levers will be held in a retracted or inactive position, and cannot cooperate with perforations in the card, when the pin-box is moved toward the card. By this arrangement any one or a

plurality of the pins may be rendered inactive, and others permitted to remain active to perform the selecting or detecting operation. When all of the pins are active so as to sort according to any perforation in a designated column, the operation is known as "complete column sorting."

In order to reciprocate the analyzer or detector pins toward and away from the 10 perforated plates 28, 29, any suitable means may be employed, but I prefer, by way of example, to employ the following means: The parallel supporting bars 45 are supported rigidly at their ends by brackets or 15 heads 72 having inwardly projecting arms 73, each of which carries a sleeve 74 slidably mounted on a post 75 which is rigidly mounted on the side frames 1, 1. Each of the brackets 72 is provided on its outer face 20 with a stud 76 to which is connected one end of an eccentric rod 77, the other end of which carries an eccentric strap 78 surrounding an eccentric 79 fixed to the shaft 13. It will be seen that when the shaft 13 25 is rotated, the pin-box will be reciprocated relative to the plates 29. The shaft 13 is driven from the shaft 17 by means of the transmission gears 16, 22, 26 and 27, as heretofore described. The arrangement and 30 timing of the elements is such that a card is fed from the magazine 3, and into the space between the plates 28, 29, while the pin-box is at such a point above the plate 28 that the pins do not enter the perforations 35 in said plate, whereupon the pin-box is caused to descend to read or analyze the card between the plates; the pin-box is then raised to permit the analyzed card to be ejected from, and another card to be received between, the perforated plates.

The pin-box is adjustable lengthwise of the bars 45 so as to locate the pins over the row of perforations in the plates 28, 29, which correspond to the column in the card 45 A, which contains a designation or item which controls the sorting operation, for example, as stated, to take position over the row of perforations corresponding to the month column on the card A.

50 One of the bars 45 is provided on its inner side with a plurality of vertical notches 45^a and the pin-box is provided with a suitable latch to cooperate with said notches to lock the box in the desired row of perforations in the pin plate. The latch preferably consists of a vertical bar 45^b (see Fig. 4) having longitudinal slots 45^c receiving upper and lower stud pins 45^d on one of the end plates 47, said bar having a key 45^e 55 adapted to enter one of the slots 45^a. The bar is normally urged upward into locking position by a tension spring 45^f, one end of which is connected to the upper stud-pin 45^d, and the other end of which is connected 60 to a pin 45^g on the bar. When the box is

to be released from the bar 45, the latch-bar 45^b is moved down until the key 45^e clears the bar 45, when the box may be adjusted lengthwise of the bar 45, and again be locked in position by the latch bar.

70 When the pin-box is projected into analyzing or detecting relation to the plates 28, 29, and the card A, the pin or pins 48 selected to respond to certain card perforations are projected through said plate and 75 card perforations and cooperate with certain setting mechanism which sets into action instrumentalities, to be hereinafter described, at the station or depository which properly should receive cards like the one 80 being analyzed by the pins 48.

The setting means is of novel construction, and in its preferred form embodies the following mechanism: Beneath the plate 29 and arranged in line with the rows of perforations which extend transversely of the machine, are a plurality of horizontally disposed thrust-receiving members in the form of bars 80, each of which consists of a vertically disposed plate 81 having a horizontal 90 flange 82 arranged beneath the plate perforations and normally adapted to contact the under face of the plate 29, there being one of said bars extending lengthwise of and beneath each row of transverse perforations in the plates 28, 29. Each of these bars 80 is provided with depending extensions 83 on the ends thereof, and to each of which extensions is pivotally connected, as at 84, one end of a lever 85, said levers being 100 each pivoted at an intermediate point on fixed pivot bars 86 which are parallel to each other and supported on brackets 87, 88 depending from transverse parallel bars 89, the ends of which are supported by angle 105 brackets 90 (see Fig. 5) secured to the under side of plate 29. One of the levers 85 is provided with an inner extension 91 provided with an end slot 92, and the other lever is provided with an inner extension 93 110 overlapping the inner end of the extension 91 and provided with a lateral lug 94 located within the slot 92, whereby said levers are caused to swing simultaneously. The normal position of the levers 85 is indicated in Fig. 3 and by the corresponding shaded elements in Fig. 5. The arrangement is such that when a pin 48 passes through a perforation in the plates 28, 29, it strikes the thrust-receiving bar 80 and moves the same 120 downward, thereby moving the outer ends of the levers 85 downward and the respective inner ends 91, 93 upward to the position shown by the unshaded elements in Fig. 5. The inner end of one of the inner extensions 125 on the levers 85, for example, the extension 93, is provided with a recess or notch 95 having an inwardly inclined face 96, and mounted on the bracket 87 is a latch member 97 having an inclined nose 98 adapted to 130

enter said recess 95 or to take a position beneath the extension 93 adjacent said recess, as shown in Figs. 3 and 5, respectively. This latch member 97 is mounted on a pivot 99 to which is rigidly connected an arm 100 carrying at its free end a roller 101 adapted to be engaged by a cam 102 fixed to and rotating with the shaft 13 heretofore described. The arrangement is such that when 10 the inner ends of the members 91 and 93 are moved upward, as heretofore described, the inclined face 96 serves to move the nose 98 of the latch out of said recess 95, whereupon the tension spring 103, anchored to the latch 15 97 at a point on the bracket 87, thrusts the locking end of the latch into position under the extension 93, substantially as shown in Fig. 5 of the drawings, whereby the levers 85 will be locked in the position shown in Fig. 5, until the cam 102 acts upon the latch to throw the same beyond the end of the face 96 into the position shown in Fig. 3, whereupon the spring 103 pulls the latch nose into engagement with the inclined face 20 96 and thereby assists in moving the inner ends of the levers downward, thereby lowering the outer ends thereof and moving the detector bar 80 back into its uppermost position, that is, closely adjacent the lower 25 surface of the plate 29. The downward movement of the detector bar 80 and the simultaneous operation of the levers 85 is employed to transmit motion to settable means, to be hereinafter described, for controlling the receipt or entry of an analyzed card at the proper receiving station or depository. For this purpose one of the levers 30 85 of each detector set is provided with a depending arm 104 working in a slot 105 in guide arms 106, and adapted to cooperate with a plunger 107 connected to a plunger shaft 108 extending through a flexible tube 109 to the point where the settable means is adapted to be operated, as will be herein- 35 after described.

It will be understood that in the preferred embodiment of my invention, there is one of the bars 80 beneath each transverse row of perforations in the plates 28, 29, so that the 40 machine will be capable of analyzing the perforations contained in the column of any card which may register with the transverse rows of plate perforations. Therefore, the invention is not limited either to the number 45 of rows of perforations in the plates 28, 29, or to the number of bars which it may be found advisable to use in a machine. It will also be understood that each such bar 80 as may be employed is provided with the locking levers 85, and that when a plurality of bars are employed, as herein shown, the latch lever 97 is in the form of a bar or plate 50 extending transversely of the length of said levers. The particular arrangement of locking bars herein shown is desirable, be-

cause it not only serves to efficiently support the bar 80, but also insures parallel motion of said bar relative to the plates 28, 29, irrespective of the point lengthwise of the bar, which may be engaged by detecting pin 70 passing through a perforation in a card.

I will now describe one form of receiving station or depository or system thereof adapted to receive cards analyzed as heretofore described, and the means operated by the shaft 108 for setting said settable means. When a card is ejected from between the plates 28, 29, it is grasped by the rollers 33 and is fed along to the series of receiving stations to be deposited in the proper station determined by the analyzing means when the card was analyzed. These stations, and the means for feeding the cards thereto and controlling the entry of cards therein, may be, if desired, substantially the same as that shown and described in the patent heretofore mentioned, but in order that my present invention will be more readily understood, I will briefly describe such receiving means. In line with the analyzing means are oppositely disposed parallel side rails 110 supported in any suitable manner from longitudinal side frames 111, and beneath said trackways are arranged a plurality of card compartments or receptacles 112 adapted to receive the cards. Between the guides or trackways are a plurality of horizontal shafts 113, there being preferably one of said shafts over each of the open upper ends of said receptacles, said shafts being mounted in suitable bearings 114 supported by said side frames heretofore described. These shafts carry rollers 115 spaced lengthwise of the shaft and rigidly secured thereto, said rollers cooperating with lower rollers 116 loosely mounted on shafts 117, the contacting surfaces of the rollers 115 and 116 being disposed in line with the plane of the path of movement along which the cards travel in passing to the receiving station. The shafts 117 are mounted in suitable bearings in the side frame. Each of the shafts 113 carries a bevelled gear 118 meshing with a bevelled gear 119 on a shaft 120 mounted in suitable bearings on the frame and carrying at one end a worm 121 meshing with a worm 122 on the end of shaft 34, whereby the said shafts 120 and 113 are driven to feed cards lengthwise of the series of receiving stations. Associated with each receiving station is means to arrest the travel of a card to be deposited at that station, which means consists of a plurality of deflectors 123 rigidly connected to a deflector shaft which, in the present instance, may be the shaft 117 carrying the loose rollers 116. Each of these deflectors 123 comprises a part 124 normally lying in line with the card trackway and covering and closing entrance to the card 125

station, as shown in Fig. 2, whereby a card not designated for any particular station will be prevented from entering said station. Each deflector bar also includes a guide member 125 which, when the deflector bar is moved upward on its pivot 117 to permit access of a card to its proper receptacle, for example, as shown in dotted lines in Fig. 2, will arrest motion of the card along the trackway and direct it into its proper receptacle.

The means for so operating the deflector bars comprises a settable means, preferably, for example, substantially that shown in said patent for determining the time of the raising of the deflector bars so that the deflector bar for any particular receptacle will be operated to receive a card for that receptacle when the card reaches the same.

20 Mounted upon one of the side supports 1 of the machine is a casing 126 for gearing, to be presently described, and containing a bearing 127, in which turns one end of a timing shaft 128, the latter also being supported in one or more bracket plates 129 arranged at intervals lengthwise of the series of receiving stations. This shaft 128 carries a gear 130 meshing with a worm 139 fixed to one end of the shaft 13 (see Fig. 3).

30 On the timing shaft 128 are fixed, one for each compartment, a plurality of timing discs 140, and disposed around each timing disc, and equal distances apart, are a plurality of tripping supports or pivots 141, on which are pivotally mounted settable tripping means in the form of cams 142, each of which is provided at its inner edge with a cam surface or projection 143. Each cam 142 is spaced from the disc 140 by means of a collar 144 mounted on the pin 141. On the free end of each settable cam is secured a pivot pin 145 on which is pivotally mounted a detent 146 provided with an outwardly pointing releasing finger 147 and an inwardly pointing detent 148 having a slot 148 provided with an active detent shoulder 149 and an inactive detent shoulder 150, either one of which is adapted to rest against a detent pin 151 mounted upon the disc 141 and located in said slot. Said finger 148 is held pressed against the said detent pin by means of a tension spring 152 connected to the said finger 148 and to any suitable fixed point on the disc 141. Upon each pin 145 there is also carried a roller 153 adapted when the active shoulder 149 engages the detent pin to engage an operating arm 154 fixed upon the shaft 117, whereby the said shaft is operated to raise the deflectors thereon and deflect a card into that compartment. After the operating arm 154 has been operated as stated, the releasing finger 147 engages the releasing pin 155 carried upon the outer end of the operating arm 154, whereby the active shoulder 149 is forced away from the pin 151 and the spring 152 causes the tripping cam and detent to move inward until the pin 151 is engaged by the inactive shoulder 150. To each of the arms 154 is connected a spring 156, one end of which is connected to the lever 154, as shown in Fig. 8, and the other end of which is anchored to a rod 156 rigidly supported on the frame, to throw said arm to return the shaft 117 and fingers 124 into position to close access to the receptacle 112.

35 Adjacent each of the timing discs is a bracket 129 having a lateral extension 158, and fixed to the bracket 129 is a plunger cylinder 159 in which is slidably arranged a setting plunger 160 having a head 161 between which and an end of the cylinder is an expansion spring 162, which exerts its force to retract the plunger 160 out of the path of movement of the fingers 148. Upon the lateral extension 158 is pivotally mounted, at 163, a bell-crank lever 164 having one arm 165 engaging the head 161, and another arm arranged to be engaged by the end 108 of the plunger wire 108 heretofore described, the end of the casing or flexible tube 109 being connected to the extension 158.

40 The gears 130, 139 are so proportioned that each time a card is analyzed by the pin-box, one of the tripping cams is just coming into operative relation to one of the plungers 160.

45 When a card is between the plates 28, 29 to be analyzed, and an analyzing pin 48 finds a perforation and presses upon the bar 80, the latter is depressed to the position shown in Fig. 5, whereupon the lever 104 actuates the plunger wire 108 to in turn actuate the lever 164 to project the plunger 160 into position to be engaged by the tripping cam 142 at that time coming into operative relation to the said plunger 160. When the bar 80 is depressed the latch 97 moves into locking relation to the extension 93 (as shown in Fig. 5), which action, by reason of the connection between the levers 93, 91, locks the arm 104 in position to maintain the wire 108 projected to hold the plunger 160 projected into the path of the tripping cam 142 until the latter is positively actuated. The timing of the cam 102 which releases the latch 97 to permit the plunger 160 to be retracted by its spring, is determined so as to not permit such retraction until it is certain the tripping cam will be actuated to project the roller 153 outward to engage the actuating lever 154. Preferably, the release does not take place until the pin-box has been retracted, the analyzed card ejected from the plates 28, 29, a new card fed to the latter, and the pin-box has descended to a point where the pin 148 is about to enter a perforation in the upper plate 28, whereby the maximum time of projection of the plunger 160 is obtained.

In view of the fact that the receiving stations or depositories 112 are placed at progressively greater distances from the analyzing means, it will require a greater length of time for a card passing from the analyzing means to reach the compartments more remote therefrom than to reach the compartments nearer the same, and provision is made for operating the deflector bar 124 for a particular compartment just at the instant that a card destined for said compartment reaches the same, so that each card may be deflected into its appropriate compartment without having to wait until sufficient time has elapsed for another card to be reflected into the most remote compartment. In order to accomplish this, it is merely necessary to place the plunger 160 associated with each compartment and its timing disc, such a distance from the associated operating arm 154, that the tripping cam which comes into operative relation with such plunger at the time the card is in the analyzer has just the time to pass from such plunger to said operating arm as the card which operates said plunger requires to pass from the analyzer to its deflector. In order to fulfil these conditions, the plungers 160 must be placed spirally around the timing shaft, the plungers associated with the most remote compartments being placed the greatest distance from the operating arm 154, such distances being measured forward from the plunger in the direction of rotation of the discs, indicated by the arrow in Fig. 7. As the practical embodiment herein described is provided with twelve compartments, and the timing discs are each provided with only six tripping cams, it is necessary that the tripping cams of one disc be placed in staggered relation with the tripping cams of the adjacent disc, so that a tripping cam on every disc will come into operative relation with the associated plunger 160 just at the instant the card is being analyzed, otherwise, some of the plungers would be operated at an instant when the point of the disc midway between adjacent cams would be opposite the plunger and no setting of the tripping cam would take place. The number of tripping cams can be either greater or less than that shown, if desired.

I believe the operation of the invention will be apparent from the foregoing, but will briefly describe the same as follows: A stack of cards to be sorted are placed in the magazine 3, and the pin-box of the analyzing means is adjusted transversely of the machine so that the row of pins 48 takes position over the row of perforations in the plates 28, 29 with which the column of a card containing the controlling perforation or perforations is adapted to register as the cards pass between the plates 28, 29. Power is then applied and the picker bar 4 feeds

the cards one at a time from the bottom of the stack to the space between the plates 28, 29. The timing is such that upon the descent of the picker bar the stop plate 47 carried thereby closes the exit from the plates 28, 29 so as to arrest movement of the card, and upon the continued motion of the pin-box the appropriate active plunger pin 48 passes through any card perforation which may be in register with the perforations in the plates beneath the plunger pins, and such plunger pin strikes or exerts its thrust upon the underlying bar 80. When the bar 80 is struck it is depressed to the position which throws the levers 85 to the positions shown in full lines in Fig. 5 and actuates the thrust wire 108 to project the plunger 160 at the station where the card analyzed is to be received. When the levers 85 are moved to the position shown in full lines in Fig. 5, the locking notches 96 pass out of engagement with the locking nose 98 on the latch 97, and the latter takes the position shown in Fig. 5, whereby the levers 85 are locked in the position to which they have been moved by the thrust of the selecting pin 48, and as a consequence the plunger 160 is held positively projected toward the tripping cams on the timing disc for a definite period of time, thereby bringing about the setting of the tripping cam just as it comes into operative relation with such plunger. When this takes place, the set tripping cam and the card which has caused its setting respectively travel toward the operating arm 154 and the deflectors 124 associated with that compartment; and because of the relation between the location of the plunger 160, the remoteness of the compartment from the analyzer, and the speeds of travel of the set tripping cam and the card, said tripping cam comes into operative relation with the operating lever 154 just before the card comes into operative relation with the deflectors, whereupon the set tripping cam operates the operating lever 154 and consequently the associated deflector and deflects the card into its designated compartment. The operating cam immediately passes on and permits the deflectors to fall, so that a card immediately following the card thus deflected will pass over said deflectors for a more remote compartment. If such card was designed for the same compartment, the deflectors will be immediately actuated again in the manner just described. As soon as the operating arm 154 has been operated, the tripping finger 147 engages the tripping pin 155, thus releasing the shoulder 149 from the detent pin 151, whereupon the tripping cam resumes its normal or retracted position. This operation is repeated until all the cards are analyzed and deposited in their proper compartment.

The plunger 160 remains projected until

it is positively assured that the tripping cam has been projected to operative position, and for this purpose is not released until the next subsequent descent of the pin-box 5 brings the pins just above the perforations in the plate 28, whereupon the cam 102 operates through the roller 101 to release the latch to permit a set bar 80 to return to its normal position beneath the plate 29, so 10 as to be in proper position to receive the thrust of the pin 48 should there be any perforation in the card permitting the same to pass therethrough and again exert its thrust upon such bar.

15 The machine may be provided with suitable means for automatically disconnecting the current supplied to the driving motor to thereby stop the machine, in the event no card is fed to the plates 28 and 29. Inasmuch as this mechanism forms no part of my present invention, I will describe it but briefly.

On the frame of the machine is arranged a casing 165^a (Fig. 6), in which are arranged switch points 166 for the current leads to the motor, and with which points cooperates a switch member 167 mounted on a pivot 168, said member being adapted to be moved into engagement with the switch points by means of a manually operated plunger 169. When the plunger 169 is depressed, and the switch member 167 is engaged with the switch points, it is held in this position by means of a trigger lever to 30 which said plunger is connected, which lever is mounted on the pivot 168 and connected to the switch lever by a spring 170, said lever 170 having a latch point 171 to cooperate with a notch 172 in a locking lever 173 fulcrumed at 173^a in the casing. The arrangement is such that when the current is to be broken manually, the latch lever 173 is moved to the left of Fig. 6, whereby the lever 170 is released and through a pin 170^b 35 is thrown into engagement by a spring 174 with the switch lever 167, whereby the latter is thrown out of engagement with the switch points. Upon one of the heads 73 is a boss 175 in which is slidably arranged a plunger 176 which extends downward through openings in the pin plates (see Fig. 3), and is connected at its lower end with 40 an operating lever 177 fulcrumed on the frame at 178. The plunger 176 is urged downward by means of a spring 179. On the plunger 176 is an arm 180 on which is a pin 181 adapted to cooperate with an opening 182 in the pin plates. When the head 73 descends and there is a card between the 45 pin plates, the pin 181 engages the card and holds the rod 176 against further downward movement; but if there is no card between the pin plates, the pin 181 passes downward through the plates and the rod

176 exerts a downward thrust on the lever 177. When the inner end of the lever 177 is moved downward, the opposite end is moved upward and lifts one end of a lever 183, fulcrumed at an intermediate point, as at 184, on the frame, the opposite end of said lever, as at 185, engaging with an arm 186 on the lower end of the trigger lever 173 which operates said lever 173 to release the switch lever and permit its spring 174 to throw it out of engagement with the points 166 and thereby break the current. On the switch lever 167 is a locking pawl 187 to engage a notch 188 in the lever 173, and moved into said engagement by a spring 189. This pawl 187 maintains the lever 173 in position to have the locking nose 171 on the lever 170 properly engage the locking notch 173.

What I claim and desire to secure by Letters Patent of the United States is:—

1. In a machine of the character described, analyzing mechanism; a receiving station; mechanism at the receiving station for receiving a card at that station; means controlled by a card being analyzed for setting said mechanism at the receiving station into operation; and means operated by the analyzing mechanism whereby said setting means is held in setting relation to the said mechanism for a definite period of time.

2. In a machine of the character described, analyzing mechanism; a receiving station; mechanism at the receiving station to receive a card at that station; means controlled by a card being analyzed for setting said mechanism into operation at the receiving station; means whereby said setting means is held in setting relation to the said mechanism for a definite period of time; and means for releasing said means when the mechanism at the receiving station has been set into operation.

3. In an apparatus of the character described, the combination of a plurality of sorting stations; an analyzer; a mechanism at each receiving station and adapted to be operated through a card in the analyzer destined for its station; means at each station to cause the operation of the said mechanism at that station so that the card is received at that station; and means operated by the analyzer for locking said means in setting position until the mechanism is in operation at the receiving station.

4. In an apparatus of the character described, the combination of a plurality of sorting stations; an analyzer; a setting means associated with each station and adapted to be operated through a card in the analyzer destined for its station; mechanism for each station adapted to be set in operation to receive a card at its station by the associated setting means; and means for

locking the setting means in setting position until its mechanism is put into operation to receive the card.

5. In an apparatus of the character described, the combination of a plurality of sorting stations, an analyzer comprising a member having rows of perforations and pin means cooperable with said perforations and registering perforations in a card, an individual setting means associated with each station and adapted to be actuated by said pin means, mechanism for each station adapted to be set into operation by the associated setting means to cause the card controlling the operation of the setting means to be received at its proper station, and means for maintaining the setting means in setting position until the mechanism is in operation to receive the card.

20 6. In an apparatus of the character described, the combination of a plurality of sorting stations, an analyzer comprising a member having rows of perforations and pin means cooperable with said perforations and registering perforations in a card, an individual setting means associated with each station and adapted to be actuated by said pin means, mechanism for each station adapted to be set into operation by the associated setting means to cause a card controlling the operation of the setting means to be received at its proper station, means for maintaining the setting means in setting position until the mechanism is set into operation to receive the card, and means for releasing the setting means when the mechanism is in operation to receive the card.

7. In an apparatus of the character described, a plurality of sorting stations, an analyzer, means for transmitting cards from the analyzer to said stations, a movable timing member, a setting means associated with each station and adapted to be operated by a card in the analyzer, settable means carried on the timing member and arranged to be set by said setting means, means for maintaining said setting means in setting position for a definite period, and means associated with each station and adapted to be operated by a set settable means as the card which operated such settable means reaches the station, to cause the card to enter the station.

8. In an apparatus of the character described, analyzing means for detecting a characteristic of a card, a receiving station for cards, timing means for determining receipt of cards at said station, setting means actuated by the analyzer for setting said timing means, and means for locking said setting means in position to set the timing mechanism.

9. In an apparatus of the character described, analyzing means for detecting a

characteristic of a card, a receiving station 65 for cards, timing means for determining receipt of cards at said station, setting means actuated by the analyzer for setting said timing means, means for locking said setting means in position to set the timing 70 mechanism, and means to release said lock and setting means after the timing mechanism is set.

10. In an apparatus of the character described, an analyzer comprising a perforated 75 plate having parallel rows of perforations adapted to register with perforations in a card to be analyzed, pin means to detect a characteristic of a card indicated by a perforation therein in line with a row of 80 parallel perforations, a plurality of receiving stations, timing means for determining receipt of cards at each of said stations, setting means associated with each row of 85 plate perforations and individual to each of said stations, said setting means being individually actuated by said detector pins when detecting a card characteristic to set said timing means, and means for locking any of said setting means in position to set 90 said timing means.

11. In an apparatus of the character described, an analyzer comprising a perforated 95 plate having parallel rows of perforations adapted to register with perforations in a card to be analyzed, pin means to detect a characteristic of a card indicated by a perforation therein in line with a row of 100 parallel perforations, a plurality of receiving stations, timing means for determining receipt of cards at each of said stations, setting means associated with each row of 105 plate perforations and individual to each of said stations, said setting means being individually actuated by said detector pins 110 when detecting a card characteristic to set said timing means, means for locking any of said setting means in position to set said timing mean, and means to release the locked setting means when the corresponding timing means is set.

12. In an apparatus of the character described, an analyzer comprising a perforated plate having parallel rows of perforations adapted to register with perforations in a card to be analyzed, pin means to detect a characteristic of a card indicated by a perforation therein in line with a row of 115 parallel perforations, a plurality of receiving stations, timing means for determining receipt of cards at each of said stations, setting means associated with each row of plate perforations and individual to each of said stations, said setting means being individually actuated by said detector pins 120 when detecting a card characteristic to set said timing means, means for locking any of said setting means in position to set the timing mechanism.

- tion to set said timing means, and means acting on the detecting stroke of the analyzing pins to release the setting means locked on the previous detecting stroke of the pins.
13. In an apparatus of the character described, a plurality of sorting stations, an analyzer comprising a plate having parallel rows of perforations, a plurality of setting means each including a bar on one side of said plate, said bars extending lengthwise of the rows of perforations therein, one of said bars being associated with each station, pin detector means projectable under control of a perforated card through said perforations to operate said setting bars, a setting means for each station and operable by one of said bars, settable means for each station adapted to be set by the associated setting means to cause a card controlling the operation of a setting bar to be received at its proper station, and means for maintaining a setting bar locked in setting position until the settable means is set.
14. In an apparatus of the character described, a plurality of sorting stations, an analyzer comprising pin detector means adapted to enter perforations in a card, thrust-receiving means adapted to be engaged by said pins when entering perforations in a card, one of said thrust-receiving means being associated with each station, a setting means for each station, settable means for each station adapted to be set by the associated thrust-receiving means to cause a card controlling the operation of a thrust-receiving means to be received at its proper station, and means for maintaining a setting means in setting position relative to the settable means until the latter is set.
15. In an apparatus of the character described, a plurality of sorting stations, an analyzer comprising a plate having parallel rows of perforations, a plurality of bars on one side of said plate, said bars extending lengthwise of the rows of perforations therein, one of said bars being associated with each station, pin detector means projectable under control of a perforated card through said perforations to operate said setting bars, a setting means at each station, settable means for each station adapted to be set by the associated setting bar to cause a card controlling the operation of a setting bar to be received at its proper station, and means for maintaining a setting means in setting position relative to the settable means until the latter is set.
16. In an apparatus of the character described, a plurality of sorting stations, an analyzer comprising a plate having parallel rows of perforations, a plurality of movable setting bars on one side of said plate, said bars extending lengthwise of the rows of perforations therein, one of said bars being associated with each station, pin detector means projectable under control of a perforated card through said perforations to operate said setting bars, a setting means for each station and operable by one of said bars, settable means for each station adapted to be set by the associated setting means to cause a card controlling the operation of a setting bar to be received at its proper station, and means for maintaining a setting bar locked in setting position until the settable means is set, and means whereby a locked setting bar is released during an analyzing movement of the pin detector means.
17. In an apparatus of the character described, a plurality of sorting stations, an analyzer comprising a plate having parallel rows of perforations, a plurality of movable setting bars on one side of said plate, said bars extending lengthwise of the rows of perforations therein, one of said bars being associated with each station, pin detector means projectable under control of a perforated card through said perforations to operate said setting bars, a setting means for each station and operable by one of said bars, settable means for each station adapted to be set by the associated setting means to cause a card controlling the operation of a setting bar to be received at its proper station, means for maintaining a setting bar locked in setting position until the settable means is set, and means whereby a locked setting bar is released during an analyzing movement of the pin detector means.
18. In an apparatus of the character described, a plurality of sorting stations, an analyzer comprising a plate having parallel rows of perforations, a plurality of movable setting bars on one side of said plate, said bars extending lengthwise of the rows of perforations therein, one of said bars being associated with each station, pin detector means projectable under control of a perforated card through said perforations to operate said setting bars, a setting means for each station and operable by one of said bars, settable means for each station adapted to be set by the associated setting means to cause a card controlling the operation of a setting bar to be received at its proper station, means for maintaining a setting bar locked in setting position until the settable means is set, and means whereby a previously locked setting bar is released just previous to engagement of said pin detector means with said bar to again set the same.
19. In an apparatus of the character described, a plurality of sorting stations, an analyzer comprising a plate having parallel rows of perforations, a plurality of movable setting bars on one side of said plate, said bars extending lengthwise of the rows of perforations therein, one of said bars being associated with each station, pin detector means projectable under control of a perforated card through said perforations to operate said setting bars, a setting means for each station and operable by one of said bars, settable means for each station adapted to be set by the associated setting means to cause a card controlling the operation of a setting bar to be received at its proper station, and means for maintaining a setting bar locked in setting position until the settable means is set, and means whereby a locked setting bar is released during an analyzing movement of the pin detector means.

5 tector means projectible under control of a perforated card through said perforations to operate said setting bars, a setting means for each station and operable by one of 10 said bars, settable means for each station adapted to be set by the associated setting means to cause a card controlling the operation of a setting bar to be received at its proper station, means for maintaining a 15 setting bar locked in setting position until the settable means is set, means whereby a 20 fully locked setting bar is released 25 mining receipt of cards at each of said stations, a setting means for each timing means, a thrust-receiving bar in line with each row of plate perforations and individual to each of said setting means, each bar being individually actuated by said detector pins when detecting card characteristics to control a setting means to set an associated timing means, parallel motion means supporting each of said bars, and means for locking any of said setting means in position to set its associated timing means. 30 35 40 45 50 55 60 65 70 75 80 85 90 95 100

the pin detector means toward said bar.

20. In an apparatus of the character described, an analyzer comprising a perforated plate having parallel rows of perforations adapted to register with perforations in a card to be analyzed, pin means to detect a characteristic of a card indicated by a perforation therein in line with a row of parallel perforations, a plurality of receiving stations, timing means for determining receipt of cards at each of said stations, a setting means for each timing means, a thrust-receiving bar in line with each row of plate perforations and individual to each of said setting means, each bar being individually actuated by said detector pins when detecting card characteristics to control a setting means to set an associated timing means, and means for locking any of said setting means in position to set its associated timing means.

35 21. In an apparatus of the character de-
scribed, an analyzer comprising a perfor-
ated plate having parallel rows of perfora-
tions adapted to register with perforations
in a card to be analyzed, pin means to de-
40 tect a characteristic of a card indicated by
a perforation therein in line with a row of
parallel perforations, a plurality of receiving
stations, timing means for determining receipt
45 of cards at each of said stations, a setting
means for each timing means, a thrust-re-
ceiving bar in line with each row of plate
perforations and individual to each of said
50 setting means, each bar being individually
actuated by said detector pins when detect-
ing card characteristics to control a setting
means to set an associated timing means,
means for locking any of said setting means
55 in position to set its associated timing means,
and means to release the locked setting means
when its associated timing means is set.

24. In an apparatus of the character de-
scribed, an analyzer comprising a perforated
plate having parallel rows of perforations
adapted to register with perforations in a
card to be analyzed, pin means to detect a 105
characteristic of a card indicated by a per-
foration therein in line with a row of paral-
lel perforations, a plurality of receiving sta-
tions, timing means for determining receipt
110 of cards at each of said stations, a setting
means for each timing means, a thrust-re-
ceiving bar in line with each row of plate
perforations and individual to each of said
setting means, each bar being individually
115 actuated by said detector pins when detect-
ing card characteristics to control a setting
means to set an associated timing means,
levers supporting each of said bars, and
means cooperating with said levers for lock-
120 ing any of said setting means in position to
set its associated timing means.

25. In an apparatus of the character de-
scribed, an analyzer comprising a perforated

means for each timing means, a thrust-receiving bar in line with each row of plate perforations and individual to each of said setting means, each bar being individually actuated by said detector pins when detecting card characteristics to control a setting means to set an associated timing means, levers supporting each of said bars, and means common to all of said levers for locking any of said setting means in position to set its associated timing means.

26. In an apparatus of the character described, an analyzer comprising a perforated plate having parallel rows of perforations adapted to register with perforations in a card to be analyzed, pin means to detect a characteristic of a card indicated by a perforation therein in line with a row of parallel perforations, a plurality of receiving stations, timing means for determining receipt of cards at each of said stations, a setting

means for each timing means, a thrust-receiving bar in line with each row of plate perforations and individual to each of said setting means, each bar being individually actuated by said detector pins when detecting card characteristics to control a setting means to set an associated timing means, a pair of levers beneath each bar, said levers being interlocked with each other at their inner ends and supporting said bar at their outer ends, and means cooperating with said levers to lock any of said setting means in position to set its associated timing means.

In testimony whereof I have hereunto signed my name in the presence of two subscribing witnesses.

WILLIAM W. LASKER.

Witnesses:

AGNES E. CUNNEEN,
C. G. LIGLMUN.
